UNITED STATES PATENT OFFICE.

ESTELL V. ALLMAN, OF KANSAS CITY, MISSOURI.

TANK CAP AND LOCK.

Application filed May 21, 1927. Serial No. 193,303.

The object of this invention is the provision of a cap for the gasoline filler tanks of automobiles which can be locked on the inlet spout for the tank to prevent the surreptitious removal of gasoline from the tank.

A further object is the provision of a cap for this purpose which is of a construction to establish a fluid tight joint between the cap and the filler spout of a gasoline tank and which is further formed with a hollow lug for the barrel of a tumbler lock, and further wherein the bolt member of the lock is removably attached to the barrel so that different sizes of such members may be employed to effectively engage the inner surfaces of tanks for different lengths of filler spouts.

To the attainment of the foregoing, the improvement consists in the construction, combination and operative arrangement of parts, a satisfactory embodiment of which is disclosed by the accompanying drawings.

In the drawings:

Figure 1 is a detail sectional view through a gasoline tank for automobiles showing my improved cap arranged and locked on the spout thereof.

Figure 2 is a bottom plan view of the cap.

Figure 3 is a perspective view of the bolt member for the lock.

Referring now to the drawings in detail, the numeral 1 designates a filler or gasoline supply tank of the type which is attached to automobiles. The tank 1 is provided with the usual inlet opening at the top thereof and this opening is surrounded by an upstanding annular flange 2, that generally is termed a filler spout.

My improvement comprises a disc member 3 having on what I will term its inner face, an outer depending annular flange 4 and an inner annular flange 5. The flanges 4 and 5 receive the spout 2 therebetween. Arranged on the inner wall of the cap, between the flanges 4 and 5 there is a compressible disc 6 which, of course, contacts with the outer edge of the spout 2.

Integrally formed with the cap, and with the inner wall of the inner flange 5 there is a lug 7. This lug has a central opening therethrough for the reception of a barrel 8. The barrel is of the type usually employed in

connection with pin tumbler locks and has openings therethrough for the reception of short pins 9 that are contacted by the spring influenced tumbler pins 10. These last mentioned pins 10 are received through suitable transverse openings in the boss 7. The inner portion of the boss is reduced and is of a substantially rectangular formation as indicated by the numeral 11. It is through these openings that the tumbler pins are arranged. The inner wall of the part 11 of the boss is depressed transversely and in this depression there is seated a plate 12 that closes the openings for the tumbler pins and against which plate the springs 13 for the tumbler pins contact.

The bolt member of the lock includes a disc head 14 and a bit portion 15. The bit has an angular extension 16 and the sides of the body of the bit are grooved, as at 17. These grooves are in a line with openings 18 in the head or disc 14 of the bolt, and the openings receive therethrough screws 19 whose shanks engage with threaded openings in the barrel 8. The grooves permit of a screw driver readily engaging the kerfed heads of the screws 19. By this arrangement it will be seen that different size bolts may be attached to the barrel so that the cap may be successfully employed upon tanks having different lengths of filler spouts 2. When the barrel is operated by the key 20 the bolt will be turned with the barrel so that its bit 16 will be brought against the inner wall of the tank, as disclosed by Figure 1 of the drawings. Of course, when the cap is to be removed the barrel is again turned but in a different direction to bring the bit to the dotted line position in Figure 1 of the drawings.

The construction is comparatively simple and the advantages thereof are well known and will be appreciated by those skilled in the art to which the invention relates.

Having described the invention, I claim:

A cap designed to provide a cover for the filler spout of a gasoline tank or the like, said cap having on one of its faces spaced annular flanges designed to receive therebetween the spout, the inner flange being integrally formed with an enlargement that is

provided with a socket, a revolute member received in the socket, a detachable angle head secured on the inner end of the revolute member, for engaging with the inner end 5 of the spout for the tank to which the spout is secured, in combination with spring influenced means for holding the revolute

member from turning and a removable plate seated in the enlarged portion of the inner flange for retaining said spring influenced 10 means in said portion of the flange.

In testimony whereof I affix my signature.

ESTELL V. ALLMAN.
